Attorney.

UNITED STATES PATENT OFFICE.

FRANZ HEINRICH BENNO STELZER, OF DRESDEN, GERMANY, ASSIGNOR TO "UNIVERSALLE" CIGARETTENMASCHINEN-FABRIK J. C. MÜLLER & CO., OF DRESDEN, GERMANY.

MACHINE FOR FORMING CIGARETTE MOUTHPIECES.

Application filed March 31, 1921. Serial No. 457,318.

To all whom it may concern:

Be it known that I, FRANZ HEINRICH BENNO STELZER, a citizen of the German Republic, residing at Dresden, Germany, have invented certain new and useful Improvements in Machines for Forming Cigarette Mouthpieces, of which the following is a specification.

This invention relates to automatic machines for the formation of mouthpieces for cigarettes, of the kind in which the mouthpiece is formed by rolling a paper strip or blank into a spiral which is subsequently inserted into one end of the paper tube or casing of the cigarette.

The paper mouthpiece strip or blank is, as has previously been proposed, rolled into the required spiral form by means of a rotating winding needle composed of two parts, viz, a needle sheath or casing and a retaining needle located therein which is arranged to grip the end of the mouthpiece strip between the retaining needle and its sheath when the strip is inserted through a longitudinal slot in the sheath.

According to the present invention the retaining needle is maintained against the needle sheath by friction or the like in such a manner that it rotates with the sheath. Before beginning the rolling of the mouthpiece strip and after the insertion of the front end of the strip into the needle sheath the retaining needle is partly rotated or rocked so as to grip the mouthpiece strip end and secure it in the needle sheath. After the strip is completely wound the needle must be rotated or rocked in the reverse direction so as to release the end of the mouthpiece strip which during the further operation of the machine is expelled from the sheath and delivers as a spirally wound mouthpiece. The partial rotation of the retaining needle against friction as above described is effected by providing on the end of the retaining needle projecting from the sheath, a finger which co-operates with a rocker element so actuated that during the rolling operation is held out from the path of the finger rotating with the sheath, but before and after completion of the rolling comes into engagement with the

finger and forces it to one side or the other. The rocker element is preferably constituted by the forked end of a rocking lever, which during the rolling operation remains stationary, in such a position that the finger connected to the retaining needle is intermediate and clear of the forked ends of the lever. At the beginning and end of the rolling operation, however, the lever is rocked to one side or the other so that one or the other of its forked ends can engage with the finger on the retaining needle, and thus force the finger in one direction or the other as it rotates.

The invention is illustrated in the accompanying drawing of which—

Figure 1 is a view in side elevation, and Figure 2 a plan view partly sectional of a portion of a machine constructed in accordance with the invention.

Fig. 3 is a detail perspective view of the needle and its cooperating parts.

Fig. 4 is a transverse section through the needle and its sheath showing their positions when receiving the paper strip from which the mouthpiece is formed.

Fig. 5 is a similar view showing the strip held by the needle; and

Fig. 6 is a similar view showing the tube so used in connection with the strip.

Referring now to the drawing it will be seen that the mechanism for forming the mouthpiece consists of a needle sheath *a* and a retaining needle *f* rotatably mounted therein. The needle sheath *a* is secured to a carrier *b* which is mounted in a bearing *c* arranged on the frame *A* of the machine. The carrier *b* is provided with a pinion *d*, with which a toothed segment *e* intermeshes through a slot in the bearing *c*. The needle *f* co-operates in a known manner with the needle sheath *a* which is provided at its operative end with an entrance slot for the end of the paper mouthpiece strip, (this portion of the sheath *a* being shown in Figure 2 as broken away). By rotating the retaining needle *f* the end of the mouthpiece strip is gripped and pressed against the side of the slot and thus held fast. The rolling of the strip into a spiral is then effected by rotating the sheath *a* and the

needle *f* is subsequently turned in the sheath so as to release the end of the mouthpiece strip which can then be stripped from the needle and inserted in the paper cigarette 5 casing.

The needle *f* is adapted to be retained in the desired position in the sheath *a* by a friction device comprising a spring *g* engaging at one end against a stop *h* secured 10 to the needle *f* and at its other end against a carrier *b* of the needle sheath *a*. On one end of the needle *f* projecting from the carrier *b* a collar *i* is secured which carries a finger *k*. The spring *g* tends to draw this 15 end of the needle *f* into the needle sheath *a*, so that the collar *i* is in frictional engagement with the end of the carrier. The spring *g* is so arranged that the friction is sufficient to ensure the retention of the 20 mouthpiece strip during the rolling operation.

In Figs. 4 and 5 in which the needle and sheath are shown on a large scale, the sheath *a* has a slot *x* through which the strip of 25 paper *y* enters and passes into a V-shaped slot *z* in the needle *f*. This strip *y* is inserted when both members *a* and *f* are at rest. After the paper strip is inserted the 30 needle *f* is turned and as the end *n* of the fork of lever *l* strikes finger *k* it carries the finger with it and causes the needle to be tightly set. The parts *a* and *f* are then 35 simultaneously rotated by turning of the carrier *b*, the needle being held in position by friction. The turning of the carrier *b* is accomplished by the meshing of segment *e* with wheel *d* and results in the pushing 40 of the strip *y* into tube *H*, through the slot *S* in said tube. It is to be understood 45 that when this occurs the slots *S* and *x* must be in radial alignment to permit the strip of paper *y* to enter both at once. After the strip of paper is set the sheath *a* is rotated thereby drawing the strip of paper 50 into tube *H* and winding it up into a spiral. When the spiral is completed the end of the paper is pulled into the tube and the other end must be released which is accomplished by returning needle *f* to its 55 initial position.

Before the rolling of the strip commences the finger *k* lies opposite to the forked end of a bent lever *l*, pivotally mounted at *m* on the frame of the machine. The ends of 55 the fork are provided with rollers *n*. The opposite end of the bent lever *l* is provided with a roller *o* which engages in the curved slot *p* formed in one side of a cam disc *q*. The curved slot *p* is provided with an 60 outward salient *r* and an inward salient *s*, so that the lever *l* during each revolution of the cam disc *q* is rocked twice in such a manner that on one occasion the fork is moved upwards and the next downwards. 65 When the fork is rocked upwards the lower

roller *n* engages with the finger *k* and presses against it. This results in a turning movement of the retaining needle *f* in the sheath *a* against friction and this turning movement effects the retention of the previously inserted end of the mouthpiece strip. 70

The lever *l* then returns to its stationary position so that the finger *k* can pass the rollers *n* of the fork during the rotation of the needle. Upon the completion of the 75 rolling operation the finger *k* is again opposite to the forked end of the lever *l* and the second rocking movement of the fork downwards takes place whereby the finger *k* is forced over to the other side, the needle *f* is therefore turned backwards in its 80 sheath and the end of the mouthpiece strip is released so that the strip wound into a spiral can be pushed out from the needle 85 sheath and inserted in the cigarette casing.

The cam disc *q* also operates a lever *t* which carries the toothed segment *e* effecting the rotation of the needle. The lever *t* by means of a roller *u* carried thereby engages in a curved slot *v* on the other side of the cam disc *q*. As the curved slots *p* and *v* occupy invariable positions on one and the same cam disc, the correct co-operation of the lever *l* and the toothed segment *e* is ensured by a simple and reliable construction. 95

Having now particularly described and ascertained the nature of my invention and in what manner the same is to be performed, I declare that what I claim is: 100

1. In a machine for forming cigarette mouthpieces, a needle sheath, a retaining needle held by friction in said sheath in both its retaining and releasing positions, a finger secured to said needle, a rocking device for engaging said finger to move said needle to one or the other of its positions, and means for turning the needle and for actuating said rocking device whereby 105 the exact operation of the needle is insured.

2. In a machine for forming cigarette mouthpieces, a needle sheath, a retaining needle held by friction in said sheath in both its retaining and releasing positions, a finger secured to said needle, a rocking device for engaging said finger to move said needle to one or the other of its positions, said rocking device comprising a 110 forked lever, one of the tines of which come into engagement with the finger on the needle at the beginning and end of the rotation of the needle to effect the winding of the mouthpiece strip. 115

3. In a machine for forming cigarette mouthpieces, a needle sheath, a retaining needle held by friction in said sheath in both its retaining and releasing positions, means for turning said needle, a finger secured to said needle, a rocking forked lever 120

for engaging said finger to move said needle to one or the other of its positions, one of the tines of said lever coming into engagement with the finger on the needle at the beginning and end of the rotation of the needle to effect the winding of the mouthpiece strip, a curved cam disk, a roller carried by said lever engaging said disk to rock said lever, and means controlled

by the cam disk for rotating the needle to wind the mouthpiece strip.

In testimony whereof I affix my signature in presence of two witnesses.

FRANZ HEINRICH BENNO STELZER.
